UNITED STATES PATENT OFFICE.

THEODORE W. FOSTER, OF PROVIDENCE, RHODE ISLAND.

DESIGN FOR A BACK FOR BRUSHES OR SIMILAR ARTICLES.

SPECIFICATION forming part of Design No. 31,121, dated July 4, 1899.

Application filed June 2, 1899. Serial No. 719,146. Term of patent 7 years.

To all whom it may concern:

Be it known that I, THEODORE W. FOSTER, of Providence, in the county of Providence and State of Rhode Island, have invented and produced a new and original Design for Backs of Brushes and Similar Articles, of which the following is a specification, reference being had to the accompanying drawings, forming part thereof.

10 Figure 1 is a view of a brush, showing my design. Fig. 2 is a sectional view of the same on the line X X of Fig. 1.

The leading features of my design consist in the raised foliated scrolls extending from the oval margin across a fillet parallel with the margin and raised floral garlands depending from scrolls, and the handle consisting in part of a straight many-sided shaft terminating at the opposite ends in foliated scroll ornaments inclosing panels.

15 In the drawings, A indicates the body of the brush, and B the handle; a, the slightly convex surface extending along the sides of the approximately oval back of the brush; b, a fillet parallel with the margin of the oval back; c c, scrolled leaves extending from the margin diagonally inward over the fillet;

d d, scrolls from which the floral garlands extend in curved lines; f, a pyramidal group of flowers into which the pendants of the garlands e e merge; g, the straight shaft of the handle, consisting of a number of flat strips or facets extending lengthwise on the shaft; h, a beaded ring extending around the end of the faceted shaft g; i, a scrolled ornament inclosing the panel i; k, the foliated crest at the butt-end of the handle, from which the foliated scrolls l extend, inclosing the panel l and surmounted by the floral pyramid m, the apex of which extends over the faceted shaft g of the handle.

Having thus described my invention, what I claim as new, and desire to secure by Letters Patent, is—

20 The design for the back of a brush or similar article substantially as herein shown and described.

25 In witness whereof I have hereunto set my hand.

THEODORE W. FOSTER.
